JULIUS B. WANTZ AND ARTHUR A. GROTHE, OF OAK PARK, ILLINOIS, ASSIGNORS TO VICTOR X-RAY CORPORATION, OF CHICAGO, ILLINOIS, A CORPORATION OF NEW YORK

RECTIFIER

Application filed May 10, 1924. Serial No. 712,483.

The subject matter of the invention herein-after disclosed relates to advances in the art of rectifying periodically varying electric currents, the invention including among its 5 objects the supplying, for rectifying high potential, of a corona-free or coronaless mechanism without corona-proof parts, and the provision of an appliance adapted to convert the entire wave, or any desired portion there- 10 of, of a periodically varying current into unidirectional flow.

Use of X-rays for purposes other than 15 photography has determined a necessity for currents of very high voltages to excite the tube, and the requirement of employment of more than the tops of current waves. High voltage rectification in conventional apparatus has been impracticable because of the 20 formation of corona and excessive arcing. The apparatus heretofore designed for use in conjunction with X-ray apparatus has selected the tops of waves only or a small portion thereof and no adequate provision for rectifying 25 the whole of each periodically varying wave, or a substantial portion thereof, has heretofore been made. The apparatus, the subject matter of this application for patent, is for the purpose of eliminating corona and preventing excessive arcing, and includes 30 measures for enlarging the proportionate amount of each wave rectified.

The objects of the invention therefore, include the adaptation of means for determining in advance the proportion or volume of a 35 current wave to be rectified; the selection of improved forms whereby arcing is reduced and corona avoided; and the production of a mechanism the proportions of which permit 40 of compactness when high voltages are employed.

These, and such other objects as may hereinafter appear, are attained by the construction, arrangement, and combination of the 45 several parts of the device to be hereinafter described and fully illustrated in the accompanying drawings, hereby made a part of this specification, and in which:—

Figure 1 is a schematic diagram of the invention as employed with an X-ray tube;

Figure 2 is an end view of a mechanism embodying the invention;

Figure 3 is a top view of such mechanism;

Figures 4, 5 and 6 are, respectively, a front elevation, a back view, and a vertical section 55 of one electrode; and

Figures 7 and 8 are, respectively, side and top views of the revolving switch;

Figures 9 and 10 are diagrammatic representations of the polarity of the electrodes 60 and the electrostatic fields formed in the switch.

Like reference characters are used to designate similar parts in the disclosure which follows and in the several views in the drawings. 65

It is well known that for successful employment of Roentgen ray tubes unidirectional currents of high potential are required. Various plans have been devolved for generating and supplying such unidirectional currents, 70 and it is now the more popular practice to employ an alternating current source and a rectifier for supplying current to such apparatus. It must be understood, however, that the invention here disclosed in conjunction 75 with an alternating current supply may be adapted for use with equal effectiveness upon an arrangement employing a direct current source.

Reference should be had to Figure 1. Ordinals 11 and 12 designate mains connected to any suitable source of alternating current of moderate voltage and having any one of the commercial periodicities. A step-up transformer is in circuit with said mains, the primary of said transformer being indicated 80 13 and the secondary 14, the latter being employed to excite an X-ray tube 15. Intermediate secondary 14 and tube 15, the rectifying switch forming the subject matter of this application is disposed.

A further examination of Figure 1 discloses that the tube 15 here shown is of the hot cathode type, and that a second transformer having a primary 16 connecting mains 85 11 and 12 and a secondary 17 adapted to heat the cathode of tube 15 is employed. The wiring scheme set forth is conventional, and may be altered without deviating from the spirit 90 of the invention.

High tension alternating current is conveyed from secondary 14 through terminals 14^a and 14^b by mains 18 and 19 to a plurality of equally spaced electrodes, identical in construction and here shown arranged in electrically connected vertical pairs, the right hand pair being designated 20 and 21, and the left hand pair, 22 and 23. Directly opposite each of said electrodes, 20, 21, 22 and 23 and spaced apart therefrom are similar electrodes, but arranged in electrically connected horizontal pairs, the upper pair being designated by the numerals 24 and 25, and the lower by the numerals 26 and 27.

The electrodes 20, 21, 22 and 23 are charged with periodically varying electro-motive force of high potential, from secondary 14 and in order to properly excite tube 15 which is in circuit with electrodes 24, 25, 26 and 27, a revolving switch is employed, such switch comprising a shaft 30 driven by a synchronous motor 31, also in circuit with mains 11 and 12.

Radial insulating arms 32, preferably oppositely disposed and two in number, project from shaft 30, to be joined at their free ends by a cross member or plurality of cross members 33, of electrically conducting material and having ball ends 34, also of conducting material, said cross members when used in series as illustrated in Figure 1, being insulated one from another by separators 35 affixed to arms 32.

The operation of the switch is manifest from an inspection of Figure 1. The shaft 30 is rotated synchronously with the generation in secondary 14 of periodically varying impulses of high potential. Upon one impulse, the path of current is from one terminal 14^a of the secondary 14 to electrode 20, through cross member 33 to electrode 24, to tube 15, the circuit being completed from tube 15 to the other terminal 14^b of the secondary 14 through electrodes 27 and 23 connected by the cross member 33 at the opposite end of the rotating switch. With the change in the sign, the rotating switch advances 90 mechanical degrees and the circuit is then from the last mentioned terminal (14^b) of the secondary 14 to electrode 22, thence through member 33 to electrode 25 and to tube 15, the circuit being completed by electrical connection through electrodes 26, the opposite cross member 33, and electrode 21 to the first mentioned terminal 14^a of secondary 14.

As the sign again changes, the rotor advances another quarter turn and the circuit is again as first described. On the succeeding change of the sign, the switch advances a quarter turn and the second described circuit is re-established. A unidirectional flow of current for exciting tube 15 is thus established.

Keeping in mind the schematic diagram of Figure 1, reference should now be had to Fig-

ures 2 and 3, end and top views of one embodiment of the invention. A suitable box or platform base A is provided, such base to be of wood or similar material sturdily constructed and suitably braced. Within the base A is a transformer B comprising primary 13 and secondary 14.

A frame C comprising vertically and horizontally disposed members, of high insulating value suitably joined one to another, the vertical members being designated C¹, C², C³ and C⁴ supports the electrodes 20, 21, 22, 23, 24, 25, 26 and 27, in the arrangement disclosed in Figure 1. Main 19 is arranged to convey high potential current between secondary terminal 14^a and electrode 21, and thence through the hollow upright C¹ of frame C to electrode 20. The connections for the other pair of alternating current electrodes 22 and 23 is from terminal 14^b to electrode 23 and thence through the adjacent upright C² of frame C to electrode 22.

On the direct current (unidirectional) side of the rectifier, electrodes 24 and 25 are electrically connected and are in circuit with a main (not shown) leading to and from one terminal of an X-ray tube, while the electrodes 26 and 27, situated beneath electrodes 24 and 25 of Figure 3 and opposite electrodes 21 and 23 of Figure 2 but not shown, are electrically connected and are joined to a second main (not shown) supplying high potential current to the other terminal of said X-ray tube. Electrodes 24 to 27 are mounted upon uprights C³ and C⁴, 24 and 25, and 26 and 27 being joined by horizontally disposed mains which are shown in Figures 2 and 3.

It will be noted that each of the electrodes 20 to 27 inclusive, (see Figures 4, 5, and 6) comprises a plane surface or disc 40 and a flange or rim 41 of a spheroidal configuration. Each electrode has a turned in edge 42, and is of a diameter in excess of that of the sphere of visible corona which would be formed about a point just before spark-over at the voltage for which the electrode is designed. The electrical connection in said electrodes is obtained through stem or stud 43, preferably projecting backwardly from the center of the contacting face of disk 40 of each electrode. Such electrodes, when of the diameter suggested or of greater diameter and because of their plane faces 40 and spheroidal rims 41, are corona proof—that is, of effective configuration and diameter whereby to prevent corona before spark-over. As the inturned edges 42 of electrodes 20 to 27 inclusive fall within the electrostatic fields formed by the said electrodes, no leakage or corona appears upon their comparatively sharp edges.

Synchronous motor 31 is disposed upon a smaller platform A' supporting the transformer D having its secondary 17 in circuit with the cathode of tube 15, and rotates shaft

30 which is journaled at its outer end in a bearing provided therefor upon an extension cross bar C^3 , between upright C^1 and C^2 .

5 Radial arms 32 of insulating material, preferably extend through shaft 30 and are tapered to reduce air resistance. Across their extremities (see Figures 1, 7 and 8) is a rectangular frame comprising cross bars 33 having ball ends 34, and separators 35, the cross 10 member 33 being of insufficient diameter and radii to prevent corona at the capacity for which the machine is designed and the ball ends 34, which may be solid, are also of insufficient diameter and radii to prevent corona 15 before spark-over. Separators 35 are of insulating material and are circumferentially grooved for the purpose of increasing their leakage surfaces.

The course of the high potential current 20 through the rectifier has been previously made clear in the description based upon Figure 1. The apparatus described is adapted for use in all types of X-ray work but more particularly to such as necessitate the use of a large 25 amount of each wave of current. By the spacing of connectors 33, that is, by lengthening or shortening separators 35, more or less of each current wave is rectified, and the whole of the wave, or substantially the whole 30 thereof, may be passed to the tube 15. As indicated a single cross member 33 may be employed, and the shape thereof may be varied. Again, a single radial arm 32 may be used, and other modifications may be had without 35 departing from the invention, the provision of a coronaless rectifying switch comprising parts that are not corona proof. The various line switches and other incidental apparatus found in commercial X-ray outfits have been 40 omitted for any one skilled in the art will instantly add, in applying the invention to a commercial purpose, such additional apparatus as is desirable for the specific problem in hand. It is also manifest that the device 45 has equal application in a direct current apparatus for supplying high potential to an X-ray tube.

Reference should again be had to Figures 1, 2 and 3. The several electrostatic fields 50 formed in the switch consist of electrostatic lines of force emanating at right angles to the surfaces of the electrodes, 20 to 27, the greatest intensity being between electrodes of opposite polarity.

55 Electrodes 22 and 23 are always of opposite polarity from electrodes 20 and 21.

Whenever the connectors 33 are intermediate two of the electrodes 20 to 23 inclusive, and two of the electrodes, 24 to 27 inclusive, 60 electrodes 24 and 25, and 26 and 27 become oppositely polarized, the polarity of said electrodes being unchanging. With the movement of rotor 32, as will be seen from Figures 9 and 10, two electrostatic fields are 65 formed between oppositely faced electrodes,

for in the position shown in Figure 9, one field exists between electrodes 21 and 26, and another between electrodes 22 and 25. As the other pairs of opposed electrodes, 20 and 24, and 23 and 27 between which the connectors 33 serve to pass current are of like polarity, no electrostatic field exists therebetween. In Figure 10, fields exist between electrodes 20 and 24, and electrodes 23 and 27, but no fields exist between the remaining electrodes, 21 and 26, and 22 and 25, for these pairs of opposed electrodes are of the same polarity and are connected by members 33.

70 It may therefore be stated that there are six electrostatic fields existent in the switch whenever the rotor 32 is in such a position that electrical connection is established between any two of the alternating current electrodes and the opposing two unidirectional current electrodes. As each of the two possible connections are established between the alternating and pulsating direct current sides of the switch, through the four connecting positions of rotor 32, there are two horizontal fields on the alternating current side of the switch, two vertical fields on the direct current side, and two transverse fields which 75 may be said to be rotating.

80 As the rotor 32 at each advance of a quarter turn and at its opposite ends connects similarly charged electrodes, the connectors 32 when conducting current always lie within a shielding influence of connected electrodes of effective radii to prevent corona before spark-over. That is, there is no preliminary corona.

85 It is, of course, to be understood that the whole switch comprises electrostatic fields, but that the lines of force described in detail here are the most intense lines of force in the switch. Corona prior to spark-over is wholly avoided by the disposition of the connectors, 90 when carrying high potential, between two corona-proof electrodes, hence it is not material that the connectors themselves should be corona-proof.

95 Thus, the most intense lines of force of the electrostatic fields of the switch on the alternating side of the switch are never parallel to the most intense lines of force on the direct current side, but always perpendicular thereto, while the lines of force of the transverse fields intermediate the alternating and direct current sides of the switch are at an angle of 90 degrees to each of the first mentioned lines. An imaginary line coincident with the 100 lines of force of greatest intensity in the several electrostatic fields would follow three directions, each at an angle of 90 degrees to the other.

105 As the electrodes 20 to 23, on one side of the switch, and 24 to 27, on the other side of the switch, are effectively insulated one from another by the air space therebetween, and are of effective radii and diameter to prevent corona, the machine here described is wholly 110 115 120 125 130

free from corona and its ill effects upon patient, operator and surrounding objects resulting from the generation of nitrous oxide and ozone.

5 The invention may therefore be said to comprise a symmetrical arrangement of the electrodes producing symmetrically disposed electrostatic fields, the insulating air space intermediate the oppositely charged electrodes being constant at all times. It is, of course, to be noted that the insulating arrangement herein employed is symmetrical with respect to the stationary electrodes, and that the rotor is of such configuration and 15 form that the disturbance incident to the movement of said connecting member between the several electrodes has a minimum disturbing influence upon the insulating arrangement thereof.

20. Claims:

1. A rotary rectifying switch for high tension current comprising the combination of relatively movable electrodes, one of said electrodes having a relatively large conducting surface and an inturned periphery whereby corona discharge is reduced, and the other comprising a bar of relatively slight diameter.

2. A rotary rectifying switch for high tension current comprising the combination of relatively movable electrodes, one of said electrodes having a relatively large conducting surface comprising a disk like portion and an inturned periphery whereby corona discharge is reduced, and the other comprising a bar of relatively slight diameter.

3. A rotary rectifying switch for high tension current comprising the combination of relatively movable electrodes, one of said electrodes having a relatively large conducting surface comprising a plane bounded by a spheroid whereby corona discharge is reduced, and the other comprising a bar of relatively slight diameter.

45. 4. A rectifying switch for high tension current comprising the combination of an electrode having a large relatively flat conducting surface and turned in edges whereby corona discharge is reduced, with a rotating 50 conducting member of relatively slight conducting surface.

5. A rectifying switch for high tension current comprising the combination of an electrode having a large relatively flat conducting surface comprising a plane and turned in edges whereby corona discharge is reduced, with a rotating rod connector of relatively slight conducting surface.

60. 6. A rotary rectifying switch for high tension current comprising the combination of relatively movable electrodes, one of said electrodes comprising a stationary plane, and having a relatively large conducting surface and an inturned periphery whereby corona 65 discharge is reduced, and the other compris-

ing a movable bar member of relatively small conducting area.

7. In a rectifying switch for high tension current, alternating current and uni-directional current electrodes comprising stationary spheroids at the opposite sides of said switch, whereby corona discharge is reduced, and a movable conducting electrode of relatively slight conducting surface intermediate said spheroids. 70

8. In a rectifying switch for high tension current, alternating current and unidirectional current electrodes comprising spaced spheroidal members whereby corona discharge is reduced, and a movable ball conductor member of a relatively small fraction of the diameter of said spheroidal member and intermediate said spheroidal members. 80

9. A rectifying switch comprising a plurality of stationary electrodes of relatively large conducting surfaces, and an electrode movable with respect thereto, said movable electrode comprising a plurality of conducting members the amount of separation of which determines the proportion of each alternate current wave to be rectified. 85

10. A rotary rectifying switch comprising spheroidal electrodes having relatively large conducting surfaces, and a movable electrode comprising conducting members of relatively small conducting surfaces and arranged in series, the amount of separation between said conducting members in series determining the proportion of each alternating current wave to be rectified. 95

11. A rectifying switch comprising stationary electrodes, and spaced opposed movable electrodes, each of the latter comprising a plurality of spaced apart conducting members insulated one from another, the amount of separation between said conducting members determining the proportion of each alternating current wave to be rectified. 105

12. In a rectifying switch, a source of alternating current, a plurality of stationary electrodes having relatively large flat plane conducting surfaces arranged oppositely to one another, and a rotor having a motor for driving it synchronously with said alternating current and carrying a conducting electrode of relatively slight conducting surfaces having a path of movement intermediate the conducting faces of said stationary electrodes. 110

13. In a rectifying switch, a plurality of stationary electrodes having oppositely arranged relatively large conducting surfaces, and a conducting electrode movable intermediate said stationary electrodes and having spherical ends connected by a cross member, 125 said spherical ends and said cross member being of a relatively slight diameter, such diameter being a small fractional part of the diameter of a stationary electrode.

14. In a rectifying switch, pairs of elec- 130

trodes of spheroidal configuration having a large conducting surface and spaced apart a distance a fraction of their diameter, and a conducting electrode comprising a cross bar of relatively slight diameter and intermediate said pairs of electrodes, said bar electrode and spheroidal electrodes being relatively movable.

15. In a rectifying switch, a conducting electrode comprising spherical terminals of relatively slight conducting surface, a cross bar intermediate said terminals and of relatively slight diameter, said electrode being movable relatively to stationary electrodes, and stationary electrodes comprising a plurality of paired spheroids of relatively large conducting surfaces and spaced apart a fraction of the diameter of said spheroids.

16. In a rectifying switch having alternating current and unidirectional current sides, a plurality of spaced disk-like electrodes, there being four of said disks at one side of said switch with parallel faces, and four at the other side of said switch similarly arranged, so that the most intense lines of electrostatic force in the opposite sides of said switch are at angles of ninety degrees to the most intense lines of electrostatic force across said switch and a movable connector for establishing electrical connection between oppositely disposed electrodes.

17. A rectifying switch having an unidirectional current side and an alternating current side, a plurality of oppositely disposed and equally spaced disk-like electrodes arranged four on each side of the switch so that the most intense lines of force on opposite sides of said switch are perpendicular to one another.

18. A rectifying switch having stationary electrodes, and a movable electrode comprising a plurality of separated conducting members insulated one from another, the amount of separation between said conducting members determining the proportion of each alternating current wave to be rectified.

19. A rectifying switch comprising opposed electrodes, and a movable intermediate electrode, said latter electrode comprising a plurality of spaced apart members insulated one from another and being spaced to rectify a predetermined or selected part or portion of an alternating current wave.

JULIUS B. WANTZ.
ARTHUR A. GROTHE.
